UNITED STATES PATENT OFFICE.

THOMAS E. CLARK AND JAMES E. CLARK, OF DETROIT, MICHIGAN, ASSIGNEES TO
CONTINUOUS TRAIN CONTROL CORPORATION, OF DETROIT, MICHIGAN, A CORPORA-
TION OF MICHIGAN.

RAILWAY-TRAIN-CONTROL SYSTEM.

Application filed December 5, 1925. Serial No. 73,318.

This invention relates to train control systems and more particularly to arrangements cooperating with block signalling systems to control the movement of trains.

5 It has been proposed to employ low frequency inductive control arrangements in former train control systems but such systems in highly congested traffic areas, where there is the greatest need for train control, 10 are unreliable due to the wide prevalence of foreign currents of low frequency.

In connection with former systems it has also been proposed to employ a receiving system on a vehicle or train including an electromagnetic device or a hot wire mechanism but these arrangements require a larger amount 15 of current to be introduced into the track circuit from the wayside stations than is convenient under all circumstances.

20 In accordance with the present invention, it is proposed to incorporate a high frequency signalling arrangement in combination with a block signalling system for the control of trains.

25 Another feature of the invention resides in the use of an electron discharge device on a moving vehicle or train, to control electro-pneumatic brake mechanism for stopping trains under predetermined conditions.

30 Other features of the invention will appear from the detailed description and appended claims.

In the drawings, Figs. 1^A, 1^B, 1^C and 1^D, when arranged from right to left in the order 35 named, diagrammatically represent a portion of a railway system divided into four block sections on certain of which sections there is indicated a receiving mechanism mounted on a locomotive or train.

40 Fig. 2 is a modified form of the invention in which a motor generator is employed to provide proper filament and plate current for the electron discharge oscillator.

Fig. 3 illustrates another modification in 45 which the filament and plate currents are derived from a power line such as a commercial source of current. In this arrangement, the filament circuit of the electron discharge devices on the locomotive extends thru the loop

or other signal collector to ensure application 50 of the brakes in the event that the circuit of the loop or signal collector is broken or otherwise placed in an inoperative condition.

Fig. 4 is a side elevation of a locomotive equipped with a receiving unit for controlling the air-brake system.

Fig. 5 is a partial front elevation of a locomotive with certain parts broken away to indicate the location and inclination of the coils on the locomotive with respect to the energized rails of the track section.

Figs. 6 and 7 are diagrams representing the magnetic field about the track rails, as well as the loop collector coils and also the locomotive wheels and axle.

Figs. 8 and 9 represent an elevation and a section, respectively, of an electrical circuit controller arranged to disable the electrical train control devices when the locomotive is operating in non-signalling territory, such as 70 at the round-house, various sections of the freight yard or other territory without control equipment.

Fig. 10 is a sectional view of an electro-pneumatic valve mounted on the locomotive 75 and adapted to be variably operated by the receiving device to control the air brake system of the train.

Fig. 11 shows the general arrangement of the receiving device together with the electrically controlled pneumatic valve and a portion of the air system all mounted on the locomotive.

Figs. 12 and 13 are sectional diagrams in which Fig. 12 shows the air brake equipment 85 in normal running position and Fig. 13 shows the air brake equipment in condition to apply the brakes.

Fig. 14 is a sectional view showing the air brake reduction valve.

Referring to the drawings, 1^A to 1^D, inclusive, the track rails 1 and 2, which are electrically bonded together, are shown divided into sections by insulating joints 3. Adjacent each junction of two sections, there is 95 provided a wayside station such as A, B, C or D including a source of power and a signal stand, which, in the arrangement shown, in-

cludes a signalling arm or semaphore to indicate in the 90° position a "clear" track condition, in its 45° position to indicate a "caution" condition, and when in its horizontal position to indicate a "danger" condition. At the wayside station, there is also provided a block signal controlling mechanism including various electrical circuits, track batteries, track relays, line relays and controlling relays, indicated in light lines and there are provided other circuits for the train control system which are indicated by heavier lines. These two groups of circuits cooperate in the signalling and the train control systems, but are shown in this manner to indicate the facility with which the train control system of this invention may be incorporated in existing block signalling systems.

In accordance with the existing practice, the tracks of each block section are normally connected to a track battery 5 located at a wayside block signal station, which battery is electrically connected to the rails at the exit end of its block section through suitable reversing switches, such as 6, to close a circuit for a polar neutral relay bridged across tracks 1 and 2 at the entrance of the block controlled by the operation of the signalling arm 4, as follows:—from one pole of the battery 5, through conductor 7 to rail 1 and from the other pole of the battery, through the conductor 8, series relay 9 and conductor 10 to track rail 2. The normal flow of current through the circuit just traced when the track rails of the block are unoccupied is limited by the comparatively high resistance of the relay 11 to a value which is insufficient to operate the relay 9, this relay 9 having windings of comparatively low resistance. When, however, the track rails 1 and 2 are connected by the wheels and axles of a train or vehicle in the block, the high resistance winding of the relay 11 is shunted by the low resistance path comprising these wheels and axles, and the current flowing through the relay 9 is thereby increased to an amount sufficient to cause the operation of this relay, for a purpose to be hereinafter described.

At the entrance of each block section, there is provided a polar neutral relay 11, the structure of which is well known, and which is normally energized by the flow of current from the track battery just referred to flowing through the track rails 1 and 2 to which it is electrically connected by wires 12 and 13. At the wayside station, there is also provided a local battery 14, which is connected to the operating mechanism of the signal arm 4 through the armatures of the associated polar neutral relay 11 in such manner that when a train occupies a block section the signal 4 at the entrance of such occupied block section drops to "danger" position. When, however, a train occupies the block one section in advance, the signal 4 is placed in its 45° posi-

tion, indicating "caution", and when neither of these blocks is occupied, the signal 4 is raised to its 90° position indicating "clear".

The electrical circuits and mechanism for controlling these movements are diagrammatically illustrated in Fig. 1^B. While the block signal mechanism may be of any well known construction, that shown in this figure is one of several types suitable for operating in applicant's system. In this arrangement, there is provided in the signal tower, a shaft 15 on which semaphore arm 4, a pair of latch wheels 16 and 17 together with a cam 18 and a gear 19, are mounted. This gear, which rotates the shaft 15 is driven by an electric motor, such as 20 and the cam 18 is arranged to operate levers 21 and 22 so that when the arm 4 is raised to the 45° or 90° positions, respectively, the lever 21, connected to the arm 23 actuates the reversing switches 6 and 24 whereby these switches are moved clockwise to one position when the arm 4 is raised to the 45° position. The lever 22, which is also actuated by the cam 18, is connected by a rod 25 to the switch 26 so that this switch is moved in a clock-wise direction when the signal arm 4 is raised to its 90° position. Suitable magnets 27 and 28 provided with pawls 29 and 30 on their respective armatures are adapted to engage suitable latches and support the arm 4 in its various positions, the latch 16 serving to hold the signal arm 4 at the 45° position and the latch 17 functioning to support the signal arm 4 at the 90° position.

When a block section such as C is in a "clear" condition, a circuit is closed from one side of the battery 14 at B, conductor 31, winding of magnet 28, conductor 36, armature 11^a, conductor 35, armature 11^a, conductor 34, armature 33^b of magnet 33, energized as hereinafter described to the other side of battery 14. With the magnet 28 thus energized, its pawl 30 engages the latch 17 to hold the semaphore arm 4 in the 90° or "clear" indicating position. As soon as a train occupies the block section C, the wheels and axle of the locomotive shunt the current to the relay 11 at B, causing it to open the circuit last described at its armature 11^a, which effects the de-energization of the magnet 28, resulting in the withdrawal of its pawl 30 which permits the semaphore arm 4 to drop under the action of gravity to its horizontal or "danger" indicating position. At the same time, the cam 18, previously referred to, operates the levers 21 and 22 to move the switches 6, 24 and 26 in a counter-clockwise direction to the positions indicated in dotted lines.

After the train has passed to block section D, the relay 11 at B again becomes energized, in this instance by reversed battery current, since the switch 6, at the preceding wayside station C is in its counter-clockwise position since the signal arm 4 thereat is in its "dan-

ger" position. This operation of the relay 11 at B by reversed current causes its armature 11^a to close the circuit from one side of battery 14 through the armature 33^b (now closed, 5 since the relay 33 is energized at this time, as will be hereinafter described), conductor 34, armature 11^a, conductor 35, winding of magnet 27, conductor 31 to the other side of battery. The motor 20 is energized in multiple 10 with this last described circuit through the conductor 37 and switch 24 whereby the motor raises the arm 4 of wayside station B to its 45° position, the "caution" position, where it is held by magnet 27 and its pawl 29. At this 15 time, the cam 18 operates through the lever 21 to move the switches 6 and 24 clockwise, to their alternative positions thereby opening at the switch 24 the motor circuit just described.

When the train has entered the block section beyond station D, since the signal 4 at station D has moved to its "danger" position, the signal 4 at the station C is raised to its 45° position and when its switches 6 and 24 are in their clear-caution (clockwise) position, 20 current flows to the relay 11 at station B to position its armature 11^a in engagement with its contact, thereby closing a circuit to the magnet 28 and to the motor 20. This circuit is traceable from one side of the battery 14, 25 conductor 31, winding of magnet 28, conductor 36, armature 11^a and its contact, armature 11^b, conductor 34, armature 33^b to the other pole of the battery. The motor 20 is actuated in multiple with the circuit just described, its 30 circuit extending from conductor 31, motor 20, conductor 37, switch 24, conductor 38 and switch 26 to conductor 36. Under the control of this circuit the motor 20 rotates the shaft 15 and the semaphore arm 4 at wayside station 40 B to the 90° position to indicate a "clear" condition, at which time cam 18 through the action of lever 22 moves switch 26 clockwise to its alternative position, thus opening the motor circuit at this point.

45 *Signal controlling transmitter.*

In addition to the equipment previously referred to at each wayside station, there is provided an electron discharge oscillator and 50 controlling circuits for impressing high frequency currents of two different wave lengths upon the tracks 1 and 2 of the block section to be controlled. The oscillator consists of a three-element vacuum tube herein referred to 55 as an electron discharge device which is provided with a filament 42, a grid 47 and a plate 53 included in an evacuated envelope. The filament 42 is heated in a circuit completed from one pole of battery 14, rheostat 60 40, filament 42, conductor 56, contact and armature *a* of relay 9 which is energized as previously described on the approach of a train, thence from armature *a* to the other pole of the battery. The plate circuit of this 65 oscillator extends from the plate 53 through the coil 54 to the positive pole of plate battery 39. The grid circuit extends from the grid 47, conductor 46, coil 45 to one side of the filament. The coils 45 and 54 are coupled so that the grid and plate circuits react on each other in a well known manner 70 to produce high frequency oscillations. The variable condenser 48 is adjustable to tune the circuits of the oscillator to transmit high frequency currents of one wave length 75 corresponding to "danger", whereas the variable condenser 49 tunes the oscillator to generate and apply high frequency current of a different wave length corresponding to "clear" to the track section whenever the polar neutral 80 relay 11 has closed its armature *c*. An additional coil 57 coupled to the coil 54 in the plate circuit of the oscillator applies the mentioned high frequency currents to the tracks 85 1 and 2 of the block section to the rear. The circuit through which these currents are thus applied is traceable from track 1, conductors 7 and 62, coil 61, coupling coil 57, condenser 58 and thence through conductor 10 to the track 2. It will be noted that the condenser 90 63 connected between the rails 1 and 2 forms a by-pass for the high frequency currents connected to the tracks 1 and 2 thereby limiting the circuit for the high frequency currents to that portion of the track circuit 95 between the condenser 63 and the exit end of the block section. The coil 61 in the high frequency circuit just described has two tuned circuits closely coupled to it. The first one 100 includes a coil 65, variable condenser 69 and a hot-wire relay 67; while the second circuit includes the coil 64, variable condenser 60 and a hot-wire relay 66. The condensers 68 and 69 are provided to tune these circuits to 105 resonance with the "clear" and "danger" high frequency currents transmitted over the conductors 59 and 62. The relays 66 and 67 are so constructed that they are energized by the high frequency currents in resonance with the circuits in which they are included. The 110 normal energizing circuit for the relay 33 may be traced as follows:—from the battery 14, conductors 31 and 71, relay 33, its contact and armature 33^a, contact 72 and armature 9^a, of relay 9, and conductor 32, to the battery 14. With either relay 66 or 67 energized, the relay 33 is retained energized during the interval that its normal operating circuit traced above is interrupted at the 115 back contact and armature *a* of the relay 9 when this relay is energized on the approach of a train. This holding circuit of the relay 33 extends from one pole of the battery 14 through conductors 31 and 71, winding of relay 33 and thence through the armature 120 and contact of either relay 66 or 67 and conductor 32 to the other pole of the battery. The last described circuit provides a safe- 125 guard in the event the oscillator fails to transmit high frequency currents through the coil 130

61 to properly control the approaching train. In the event of such failure, both relays 66 and 67 at, for example, the signal station B, become inert with the result that the holding circuit of relay 33 traced above is opened causing this relay to become de-energized and its armature 33b opens the circuit which has been maintaining the latch magnet 27 or 28 operated so that the arm 4 drops to 10 its "danger" position. With the movement of the arm 4 to the danger position, the switch 6 is reversed, thus opening the polar contacts 11c and 11d of the relay 11 at the entrance end of the block B to the rear. The 15 opening of the contact 11c disconnects the variable condenser 49 from the grid-filament circuit of the vacuum tube 43 and thus causes the transmission of oscillations of "danger" frequency to the track rails 1 and 2 of the block 20 section A through a circuit including the coupling coil 57, coil 61, conductors 62 and 7, the track rails, conductors 10 and 59 and condenser 58. Thus the system is protected against the failure of the train control current 25 transmitter, as the failure of a transmitter to energize the track rails of a given block section results in the transmission of a danger impulse to the track rails of the next section to the rear.

30 The relays 33 are preferably made slow acting, as represented in the drawings, by any suitable means, so that the armatures thereof do not disengage the stationary front contacts for a predetermined time interval after the de-energization of the relay windings. The purpose of this slow acting feature is to insure that the contacts of the relay 33 remain closed as a train enters the block section with which this relay is associated. As 35 a train enters a given block section, say, the section B, the relay 9 is energized, raising its armature 9a. As the armature 9a disengages its back contact 72, the normal energizing circuit for the relay 33 is broken, and the holding circuit through the contacts of relays 66 or 67 is not completed until the filament 42 of the vacuum tube 43 is energized by the engagement of the armature 9a with its front contact. During this period of movement of 40 the armature 9a from its back to its front contact, the contacts of the relay 33 are maintained closed by the slow acting feature referred to above.

55 In the alternative arrangement illustrated in Fig. 2, a different source of plate current is provided. In this modification a dynamotor 239 is connected by wires 231 and 256 to wires 31 and 56 respectively to function whenever the vacuum tube is energized. The high voltage output of this dynamotor is connected by conductors 241 and 255 to the common conductor 41 of the plate and coil 54 respectively.

60 In the modification shown in Fig. 3 there is indicated a wayside power line, the conductors of which are designated 301 and 304.

Such an arrangement may be used where there is a cheap source of current, such as is available in hydro-electric power territory. In this arrangement, upon the approach of a train, the armature 9a is closed 70 by the energization of the relay 9. The closure of this armature effects the energization of the relay 309, which in turn closes its armature a to apply a source of power from power conductors 301 and 504 to the plate 75 circuit of the electron discharge oscillator 43, and to energize the filament circuit including the filament 42, rheostat 340 and transformer winding 314. Otherwise the operation of this oscillator functions in the same manner as 80 the oscillator of Fig. 1.

Signal receiver.

The high frequency currents, which have been impressed upon the rails 1 and 2 of a 85 track section by the operation of the oscillator, result in the presence of a magnetic field about each of the rails as indicated in Figs. 6 and 7. The presence of this magnetic field is used to control receiving equipment on the 90 locomotive which in turn variably controls various signals in the locomotive cab and also an electro-pneumatic valve to operate the air brake system of the train. In order to apply signals to a receiver, there is mounted 95 a signal interceptor 100G attached to the locomotive buffer beam just ahead of the front axle but back of the pilot in the magnetic field surrounding the rail 1, while a similar signal interceptor 100R is similarly supported 100 on the other side of the locomotive within the magnetic field surrounding the rail 2.

In the present arrangement the signal interceptors 100G and 100R are shown in the form of loops or coils, but it is to be understood that the invention is not limited to this arrangement. The signals intercepted by the coils 100G and 100R are translated by electron discharge devices 101R and 101G which actuate relays to light various signals 110 in the cab and to effect train control valves by means of certain circuits which are illustrated in Figs. 1^A and 1^D. It will be noted that the collector loop 100R is included in the input circuit terminating in the grid and filament of the electron discharge tube 101R, while the loop collector 100G is included in the input circuit terminating in the grid and filament of the electron discharge tube 101G. The loop collector 100G is shunted by the variable condenser 102G which serves to tune the input circuit of its electron discharge device into resonance with the high frequency waves transmitted by the oscillator, indicating a "clear" condition. Similarly the loop 115 collector 100R is shunted by a variable condenser 102R which likewise serves to tune the input circuit of its electron discharge device to resonance with the high frequency currents indicating a "danger" condition. 120

6 The filaments of electron discharge devices 101R and 101G are heated in series by current from a double voltage head light generator 109 which applies this heating current 10 over conductor 112, rheostat 131, and thence through the filaments in series, conductor 122, resistance 123, to the other terminal of the generator.

10 The grid condenser 103R in series with the mentioned input circuit applies potential corresponding to the high frequency signalling waves on the grid of the electron discharge tube 101R, during the period that the 15 loop collector coil 100R on the locomotive is in the magnetic field of the energized zone of the track rail circuit. The grid leak 104R in the form of a high resistance connected between the grid and filament allows the negative charge to leak from the grid when the 20 collector coil 100R has passed out of the magnetic field. A similar grid condenser 103G and a grid leak 104G function in a similar manner in connection with the electron discharge device 101G.

25 Normally a plate current is flowing in the plate circuit extending from the plate of the electron discharge device 101G, over conductor 106, winding of relay 107G, conductors 151 and 108, high voltage positive terminal 30 of the head light generator 109 and thence over conductor 122, through the filament of device 101R to the filament of the electron discharge device 101G. Similarly, plate current flows in a circuit extending from the 35 plate of the electron discharge device 101R, through the winding of relay 107R, conductor 110, armature 107R—b, conductor 108 to the high voltage side of the generator 109 and thence over conductor 122 to the filament just 40 mentioned. It should be pointed out at this time that the relay 107R of this plate circuit is initially energized through the contact *c* of the lock switch 136, which is closed manually by a key while the locomotive is in 45 nonsignalling territory, this circuit being traceable as follows: from the generator 109 to contact *c* of the switch 136, conductor 110, relay 107R, to the plate of the vacuum tube 101R, and thence from the filament of this 50 tube to the generator 109. It has been pointed out how plate current is normally passing through electron discharge devices 101R and 101G. When, however, the loop collector 100R encounters the magnetic field of a 55 "danger" signal in the energized zone of the track circuit, the grid of the electron discharge device 101R accumulates a negative charge which decreases the plate current of the plate circuit including the relay 107R.

60 During the interval that the relay 107R is deenergized, its armature *a* closes a circuit from the generator 109, conductor 192, normal contacts of the key 111, conductor 113, armature *a* and back contact of relay 107R, 65 conductor 120, relay 121, and conductor 122,

to the generator 109. The momentary energization of this relay 121 closes a locking circuit for itself from conductor 120 through armature 121*a*, conductor 124, armature 107G—*a* to conductor 112, thereby retaining 70 itself locked energized until this last described circuit is opened by the reception of a "clear" signal which effects the de-energization of the relay 107G. When the relay 107G retracts its armature *a*, the holding circuit 75 for the relay 121 is opened, effecting the de-energization of this relay.

76 The relay 121 when energized closes a circuit from conductor 112, armature 121B, conductor 125, and the red cab light 126R, thence 80 through conductor 127, resistance 128 to generator 109. The lighting of this cab light is a danger signal operated by the receipt of high frequency current which is effective to indicate the "danger" condition. When, however, the "clear" condition exists, the high frequency current to which the electron discharge device 101G is responsive, effects the 85 operation of this device which momentarily de-energizes relay 107G to close a circuit 90 from generator 109 over conductor 112 through armature 107G—*a*, conductor 129 to the "green" cab light 126G and thence to conductor 127, to the other terminal of the generator. From this it will be seen that the 95 green cab light is a brief indication existing only during the interval that the coil 100G is in the field of a "clear" signal and during this interval the circuit of relay 121 is opened at the armature of relay 107G. At this time 100 choke coil 130 is shunted across the conductors 112 and 124 to protect the contact points of armature 107G—*a*.

105 The filament circuit of electron discharge devices 101R and 101G includes the resistance 131 connecting conductor 112 to conductor 122, including both of the filaments in series. It will thus be seen that the failure of either filament opens the plate circuit of both electron discharge devices, resulting 110 in de-energizing relays 107R and 107G. The vehicle brakes are controlled by an electro-pneumatic valve, which is opened to effect a brake application as hereinafter 115 described, by the de-energization of the valve magnet 118. The magnet 118 is normally energized through the following circuit:—from the generator 109, conductor 119, winding of the magnet 118, air switch 117, conductor 116, the normal contacts of the reset 120 key 115, conductor 114, armature 107R—*a*, conductor 113, normal contacts of forestalling key 111, and conductor 192, to the generator 109. Thus the de-energization of the 125 relay 107R breaks the energized circuit to the magnet 118, and causes a brake application acting to stop the train, unless the engine man forestalls this action by depressing the key 111 as hereinafter described.

130 The mentioned "forestalling" key nor-

mally closes a circuit from the low voltage terminals of the generator 109 through conductors 112 and 113, armature 107R—*a*, conductor 114, normal contacts of the reset key 115, thence through conductor 116 and air operated switch 117 (shown in detail in Fig. 12) through the magnet 118 of the electro-pneumatic valve mechanism and conductor 119, to the generator. In this way the mechanism 118 is held actuated and its valve is inoperative to apply the air brakes. The circuit for the magnet of the valve mechanism 118 is thus controlled at the armature of relay 107R so that if a "danger" signal is received, this relay opens the holding circuit of the valve mechanism 118 and if the "forestalling" key is not promptly depressed, the magnet of the mechanism becomes de-energized to set into operation the air brake mechanism (shown in detail in Fig. 11).

As soon as the "danger" signal 126R is lighted, the engineman must depress forestalling key 111 promptly in order to forestall application of the air brakes. The air-operated switch 117 is adapted, as will be described, to open the circuit including conductor 116 and the electro-pneumatic valve 118, after a predetermined interval, during which interval the forestalling key must be depressed since after the circuit is opened at switch 117 it cannot be closed again by depressing the forestalling key 111, but may be closed by using the reset key 115. This last key, when depressed, momentarily connects conductor 114 to conductor 134, and thence through armature 121c and conductor 135, which connection just traced serves as a shunt around the switch 117 and thereby prevents de-energization of the valve mechanism 118. This reset key 115 may be sealed to prevent common use as the forestalling key is sufficient if the engineman is alert.

In the system as shown in Figs. 1^a to 1^d, inclusive, the signal at station D indicates a "clear" condition ahead and the train 155 adjacent to block station is intercepting on its loop collector 100G, the high frequency wave indicating a "clear" condition through the thermionic device 101G and the relay 107G which effects the lighting of the green cab signal 126G to show the "clear" condition. The axle of the train 155 short-circuits the battery 5 of block station D to de-energize the polar neutral relay 11 at the block signal station C which drops its semaphore signal 4 to the "danger" position. Since no train occupies the block section C, the battery 5 connected through the track circuit by the reversing switch 6 in block section C energizes the relay 11 at station B to move its armatures *c* and *d* counter-clockwise, which raises the signal arm 4 at section B to 45° indicating a "caution" condition. This operation of the

last mentioned semaphore arm moves switch 6 at station B to its normal position, which normally would position the signal arm 4 at block station A to indicate a "clear" condition. At this time, however, there is a train 156 passing the signal station at block A and its axles are also across the rails 1 and 2 in block section B thereby short-circuiting them and effecting the de-energization of the polar neutral relay 11 at station A. This relay 11 on de-energization causes the semaphore arm 4 at station A to pass to the "danger" position and the oscillator at that wayside station transmits high frequency current corresponding to the "danger" condition from the time the loop collector coils 100 have passed the insulating joints 3—3 until all the axles of the train have passed these joints.

As an additional safety precaution against failure of the locomotive equipment, the circuits through the forestalling key and reset key when in normal position are arranged to prevent improper use, such as "plugging" or "tying" down to avoid the necessity of acknowledging the "danger" signal. If the forestalling key 111 is "tied" down, the circuit to the electropneumatic valve 118 is opened between conductors 113 and 116 thereby de-energizing the electropneumatic valve. If the reset key 115 is "tied" down while the relay 121 is energized, the first "clear" signal which de-energizes said relay opens the circuit between conductors 134 and 135 at the armature 121c, to effect the de-energization of the electropneumatic valve 118. It will be understood that the de-energization of this valve by either of the above methods results in the automatic application of the brakes.

The locomotive equipment as shown in Fig. 2 is the same as that of Fig. 1 except that two batteries 209 and 309 are used to supply current to the filaments and plate voltage for the electron discharge devices instead of the double voltage generator shown in Fig. 1.

The locomotive equipment shown in Fig. 3 is slightly different from that shown in the other figures and illustrates a safety feature which may be incorporated in the circuit of the loop collector coil such as 100R. If the danger loop collector coil 100R should become displaced, it might be impossible for this coil to receive a danger impulse from the track, and in order to insure that the mechanical displacement of this collector coil, as well as a break in its electrical circuit, will produce a stopping effect on the vehicle, the energizing circuit for the filaments of the electron discharge devices is connected in series with the coil 100R, and a switch 300 is included in this circuit. This switch 300 is suitably arranged to be opened by a mechanical displacement of the loop collector coil, and it will be apparent that with this arrangement, a displacement of the coil 100R, or a

break in the electrical circuit through this coil, will open the filament circuit of the electron discharge devices 101R and 101G, thus deenergizing the relays 107R and 107G, causing an automatic brake application as described above.

Air brake control mechanism.

As shown in Fig. 4, there is mounted 10 on the locomotive, air brake control mechanism shown in detail in Fig. 12 in its normal position and in Fig. 13 in its operated position. In the cab of the locomotive "clear" and "danger" cab lights 126, as well as an 15 electropneumatic valve mechanism 118, also the reset key 115 and the forestalling key 111, are positioned before the engineman.

The electropneumatic valve just referred to is shown in detail in its normal energized 20 position in Fig. 10. The case 400 of this valve is mounted on a bracket 401 through which air passes to port 402 connected to the main air reservoir and port 403 connected to the control valves. Port 403 leads below and 25 above a valve seat 404, with which a valve stem 405 cooperates. This valve is normally held open as hereinafter described but may be closed under the action of spring 406 engaging the cap 407 whenever the electropneumatic valve is de-energized. The inlet valve stem 405 is depressed by the exhaust valve stem 408 normally held in engagement with the valve seat 409 by pressure from thrust rod 410. This last mentioned rod is depressed by armature 411, which is attracted 30 by the core 412 when the coil 413 of the electromagnetic valve is energized. The electrical connections to this coil 413 are completed through binding posts such as 414, one of 40 which is shown threaded into the terminal 415 inserted in spool 416, and insulated from the case 400 by block 417. An additional port 418 from the top of exhaust valve seat 409 is connected by a pipe 419 to an air whistle 420 in the cab, whereby an audible signal is given to the engineman during the interval 45 after the de-energizing of the electro-pneumatic valve 118. The port 403 connects through the train pipe 421 to the air-operated switch 117, a control reservoir 422 and to 50 cylinders 423 and 424 of valves 425 and 426 respectively as shown in Figs. 12 and 13 whereby air from the main reservoir is normally admitted to these interconnected devices through seat 404 when the electropneumatic valve 118 is energized, but air from these interconnected devices escapes through seat 409 and sounds the whistle 420 when the electropneumatic valve 118 is de-energized. 55 The escape of air at this time is retarded by the small area between the stem 403 and the seat 409 whereby sufficient pressure is retained for a short interval during which the engineman, if alert, may depress the fore-

stalling key 111 and again energize the electropneumatic valve 118 before an application of the air brakes has been started. But should this time interval pass before the forestalling key is depressed and the air escaping from switch 117 has allowed the latter 70 to open the electrical circuit to the electropneumatic valve 118, said circuit may be re-established only by depressing the reset key.

As illustrated in detail in Figs. 12 and 13, the valves controlled by the air pressure and 75 exhaust, as just referred to, are effective as follows.—In the normal running condition, the air in the cylinder 423 raises the piston 427 which in turn lifts the stem 428 from the seat 429 and the pressure in cylinder 424 80 moves the piston 430 to the left, which thereupon moves the slide 431 and the stem 432 to the left.

The valve 425 is connected between the usual engineer's air brake valve 433 by pipe 85 434 and to the brake pipe 435, and in normal position does not interfere with the manual control of pressure in such pipe 435. When, however, valve 425 is in the brake application position, as shown in Fig. 13, the stem 90 428 drops to seat 429 to prevent recharging of the brake pipe 435 to release the air brakes, although pressure in such brake pipe may be reduced to make an application of the air 95 brakes. This reduction in brake pipe pressure occurs as soon as the pressure in pipe 434 has been reduced by the operation of the engineer's brake valve, to a point at which the brake pipe pressure will overcome the pressure of the spring 436, and lift the valve 428 100 from its seat 429.

A by-pass around the valve 425 is normally closed by sealed cut-out cock 437, which may be opened by breaking the seal 438, in case of failure of the train control apparatus. The 105 usual "double header" cock 439, in pipe 435, is retained for blocking the engineer's valve when the locomotive is coupled into a train, handled from another locomotive.

A pipe 440, connects from brake pipe 435, 110 through strainer 441 and pipe 442 to top of slide 431 and through port 443 to the bottom of cylinder 444 in which piston 445 normally presses stem 446 in seat 447 as equal air pressure is admitted to the top of cylinder 444 through port 448 (Fig. 14) and slide 431. The top of cylinder 444 is also connected through port 449 (Fig. 14) and pipe 450 to a reduction reservoir 451, and to the bottom 115 of diaphragm valve 452, thence normally through pin valve 453 and pipe 454 to port 455 under slide 431. The top of diaphragm valve 452 is connected by pipe 456 to holding reservoir 457, and to port 458, beyond stem 432. In this way air brake pipe pressure is normally admitted to reservoirs 451 and 457 and interconnecting pipes 450 and 456, as well as above diaphragm 459 and below dia-

phragm 460. Inasmuch as the diaphragm 459 is smaller than the diaphragm 460, equal air pressure on these surfaces raises the diaphragm and opens pin valve 453, admitting

5 the said air pressure to pipe 454 and port 455.

The de-energization of the electropneumatic valve 118, releases armature 411 (Fig. 10) thereby changing the position of stems 405 and 408, to close on seat 404 and open 10 from seat 409 respectively. Thus main reservoir air is no longer admitted to port 403 but this port, and the interconnected cylinders 423 and 424 and reservoir 422 are exhausted through air whistle 420 to sound an alarm 15 during which, if he is alert, the engineer may depress the forestalling key thereby closing the circuit to valve 113, as previously described. However, should the air thus escaping through whistle 420 reduce the pressure 20 in air control switch 117 to the point at which this switch opens the circuit, the forestalling key will be ineffective and an application of the air brakes will be made, as hereinafter described.

25 After the air is exhausted from cylinders 423 and 424, the pressure within valves 425 and 426 will force the pistons 427 and 430 to the position shown in Fig. 13, and at the same time positions slide 431 to cut off port 30 448 and connect port 455 to a restricted opening 461. Air in reservoir 451 and under diaphragm 460, is slowly exhausted through opening 461 until the reduced pressure under this larger diaphragm 460 is balanced by the 35 maintained pressure (pin valve 432 being closed) above the smaller diaphragm 459 plus the adjustable pressure of a spring 462, bearing on said diaphragm 459. This balancing of the mentioned pressures, closes pin valve 40 453 and retains the remaining pressure in reservoir 451 and the interconnected upper portion of cylinder 444 above piston 445.

45 Thus a predetermined reduction of the pressure on the top of piston 445 (see Fig. 14) is made during a limited interval and this reduced pressure is overbalanced by the 50 brake pipe pressure below this piston, so it is raised to unseat the stem 446. The unseating of this stem allows brake pipe pressure to escape through the restricted opening 463, until the pressures above and below piston 445 are again equalized.

55 The action of this piston is similar to the functioning of the usual equalizing valve of air brake systems of the automatic type in common use and has the same effect, that is, a reduction of brake pipe pressure makes an application of the air brakes. The engineer cannot prevent such an application of the 60 air brakes by recharging the brake pipe since check valve 428 is no longer supported by piston 427, but closes on seat 429. However, in an emergency, the brake application may be increased by the engineer by making a

reduction from the brake pipe through check valve 428.

Terminal lock switch.

A terminal lock switch 136 controlling the circuits of the engine equipment is provided 70 to place the relays and other circuits of the locomotive in operative position before it is released to the crew. This switch consists of a lock switch unit illustrated in Figs. 8 and 9 and comprises three contact switch 75 arms *a*, *b*, and *c* actuated by a cam 137 on the tumbler of a standard lock 138. When the key is withdrawn from the lock, the switch contacts are opened, but when it is in the lock 138 and turned to the locked position as indicated in Fig. 9, all of the contacts are closed. The contact arm *c* at this time extends from conductor 108 to conductor 110 thereby performing the function of energizing relay 107R through a circuit, which may be traced 80 as follows:—from the generator 109, conductor 108, contact arm *c* of switch 136, conductor 110, relay 107R, the plate of the vacuum tube 101R and the filament of this vacuum tube, to the generator 109. The contact arm 90 *b* extending from conductor 112 to conductor 135 accomplishes the same result as the reset key 115, that is the shunting of the air operated switch 117 and the energization of the 95 electropneumatic valve 118. This energizing circuit for the magnet 118 may be traced as follows:—from the generator 109, conductor 119, magnet 118, conductor 135, contact 136*b* and conductor 112, to the generator 109. The contact arm *c*, however, extends conductor 112 to conductor 125 and serves to light 100 the “danger” cab light 126R to give a warning to the key holder to withdraw the key before delivering the engine to the crew. This lighting circuit extends from one terminal of the generator 109, conductor 127, light 126R, conductor 125, contacts *a* of switch 136, conductor 112, to the generator 109. 105

We claim:

1. In a train control system, a track electrically divided into sections, means including a tuned oscillatory circuit associated with each section for applying high frequency alternating current to the rails of such section only when a vehicle is travelling in such section, means for varying the character of such high frequency alternating current in accordance with traffic conditions in advance, and vehicle carried means for operating control devices in accordance with the character of the high frequency alternating current in the track rails.

2. In a train control system, in combination with track rails electrically divided into sections, means including a plurality of tuned circuits associated with each section for applying high frequency alternating current

to the track rails thereof only while a vehicle is travelling in said section, means for varying the wave length of such current in accordance with traffic conditions in an adjacent section, and vehicle means for controlling a vehicle in accordance with the wave length of the alternating current in the track rails.

3. In a train control system, in combination with track rails electrically divided into sections, means including a plurality of tuned oscillatory circuits associated with each section for applying high frequency alternating current to the track rails thereof only while a vehicle is travelling in said section, means for varying the wave length of such current in accordance with traffic conditions in the first two sections in advance of any given section, and vehicle means for controlling the vehicle brakes in accordance with the wave length of the alternating current in the track rails.

4. In a train control system, in combination with electrically continuous track rails divided into sections by insulating joints, means associated with each section for applying alternating current to the track rails in series at the exit end of such section, said current being applied only while a vehicle is located in such section, means for confining the alternating current to the track rails of a portion of said section near the exit end thereof, and vehicle means responsive to said current in the track rails for operating vehicle control devices.

5. In a train control system, in combination with track rails electrically divided into block sections, means associated with each section for impressing a high frequency alternating voltage between the track rails at the exit end thereof only while a vehicle is located in such section, a condenser connecting the track rails near the exit end of each section for permitting the flow of high frequency alternating current therebetween, and vehicle means responsive to said high frequency current for operating vehicle control devices.

6. In a train control system, a track electrically divided into sections, a signal station at one end of each section, a signal at said signal station, circuits for variably operating said signal in accordance with the condition of a track section in advance, a relay controlling said circuits, a high frequency generator for applying high frequency currents to the tracks of the first track section to the rear of said signal, and means responsive to the failure of said high frequency generator for disabling said relay.

7. In a train control system, in combination with track rails electrically divided into sections, wayside signals associated with each section and controlled in accordance with traffic conditions in advance for selectively producing a favorable and an unfavorable indication, a source of alternating current asso-

ciated with each signal for selectively transmitting currents of different frequency corresponding to favorable and unfavorable traffic conditions to the track rails of the first section to the rear of said signal, means associated with each signal for controlling the frequency transmitted to the track rails of the second section to the rear of said signal in accordance with the indications of said signal, and means for causing each signal to indicate unfavorable traffic conditions upon the failure of the source of alternating current associated therewith.

8. In a train control system, a track electrically divided into sections, a control relay and a source of direct current connected across the rails of each section, said relay arranged to have its circuit closed on the approach of a train, an electron discharge oscillator provided with a tuned output circuit and a filament circuit, said output circuit being conductively coupled to said track section, and means including said relay for closing said filament circuit.

9. In a train control system, in combination with means for creating, along the trackway, an alternating magnetic field of a frequency corresponding to traffic conditions in advance, a car carried receiving circuit responsive to said magnetic field including the input circuit of an electron tube having a filament, train control means controlled in accordance with traffic conditions by the output circuit of said tube, and means for insuring the integrity of said receiving circuit comprising a circuit including in series therewith a portion of said receiving circuit for supplying current to heat the filament of said electron tube, whereby the failure of said portion of said receiving circuit renders said electron tube inoperative.

10. In a train control system, in combination with track rails supplied with alternating currents of a frequency corresponding to traffic conditions ahead, a car carried apparatus comprising an electron discharge device having a filament, an input circuit and an output circuit for said device, train control means controlled by said output circuit, a receiving coil connected in said input circuit and responsive to said alternating currents in the track rails, a circuit including said receiving coil for supplying heating current to the filament of said electron discharge device, and means included in said input circuit and said heating circuit for opening said circuits if said receiving coil is mechanically displaced.

11. In a train control system, car carried apparatus comprising a receiver including an electron discharge device having an input circuit and an output circuit, train control mechanism normally held operated by current in said output circuit, and trackway means responsive to traffic

conditions for inducing voltages in said input circuit, said induced voltages in said input circuit causing the current in said output circuit to be reduced to a value insufficient to 5 maintain said train control mechanism operated.

12. In a train control system, in combination with track rails divided into sections, a track relay responsive to traffic conditions 10 ahead associated with each of said sections, means including a high frequency generator associated with each of said track sections and controlled by the track relay of the first section in advance to impress high frequency 15 currents of different wave lengths on the track rails of each track section in accordance with traffic conditions ahead, and car carried apparatus comprising an electron discharge device, a control relay normally energized by a circuit including said electron discharge device and means for diminishing the 20 flow of current through said electron discharge device and thereby de-energizing said relay in response to a current of predetermined 25 wave length flowing in said track rails.

13. In a train control system, in combination with track rails divided into sections, a track relay responsive to traffic conditions ahead associated with each of said sections, means including a high frequency generator associated with each of said track sections and controlled by the track relay of the first section in advance to impress high frequency 30 currents of different wave lengths on the track rails of each track section in accordance with traffic conditions ahead, and car carried apparatus comprising a plurality of electron discharge devices, a plurality of control relays each normally energized by a circuit including one of said electron discharge devices, and means for selectively diminishing the 35 flow of current through one of said electron discharge devices to selectively de-energize said relays in response to the wave length of the high frequency current flowing in said 40 track rails.

14. In a train control system, a track divided into sections, a signal station for each section, a polar neutral relay at each signal station variably operated in accordance with the occupied or unoccupied condition of an adjacent track section, an electron discharge oscillator and circuits therefor at each signal station arranged to deliver high frequency 50 currents of different wave lengths to the rails of its track section depending upon the operation of the polar neutral relay associated therewith, said high frequency currents being impressed on the rails of a portion of a track section in order to develop a magnetic field about said rails, a train on said track section provided with two electron discharge devices, each electron discharge device being provided with an output circuit having a signal relay therein and a tuned input cir- 55

cuit including a collector coil, said coils being positioned in the magnetic field around said rails when the train is passing over the energized portion of the track section, means on said train including a signal controlled by 70 one of said signal relays, a second signal and an electropneumatic switch controlled by the other signal relay, and brake equipment normally under the control of said electropneumatic switch. 75

15. In a train control system, a track electrically divided into sections, a signal station at one end of each section, a polar neutral relay at each signal station variably operated by currents over an adjacent track section from a signal station associated with said adjacent track section, an oscillator at each station arranged to impress high frequency currents of different wave lengths on its track section under the control of its polar 80 neutral relay, a locomotive provided with a brake system, electron discharge devices on said locomotive, each electron discharge device being provided with a tuned input circuit and an output circuit, a grid condenser and a grid leak for each input circuit, a signal relay in each output circuit, two signals on said locomotive, each indicating a different track condition, each signal relay controlling one of said signals, an electropneumatic switch governed by one of said relays, said electropneumatic switch functioning to effect the application of said brake system, and a forestalling key to render the operation of said electropneumatic switch ineffective. 90 95

16. In a train control system, a track electrically divided into sections, a signal station at one end of each section, a polar neutral relay at each signal station variably operated by currents over an adjacent track section from a signal station associated with said adjacent track section, an oscillator at each station arranged to impress high frequency currents of different wave lengths on its track section under the control of its polar neutral relay, a locomotive provided with a brake system, electron discharge devices on said locomotive, each electron discharge device being provided with a tuned input circuit and an output circuit, a grid condenser and a grid leak for each input circuit, a signal relay in each output circuit, two signals on said locomotive, each indicating a different track condition, each signal relay controlling one of said signals, an electropneumatic switch governed by one of said relays, said electropneumatic switch functioning to effect the application of said brake system, a forestalling key to render the operation of said electropneumatic switch ineffective, and a lock switch for removing said electron discharge devices from signal control. 110 115 120 125

17. In a train control system, in combination with track rails divided into sections, means including a source of high frequency 130

alternating current associated with each section, control means associated with each section and acting under unfavorable traffic conditions to initiate the operation of said 5 source to transmit a predetermined high frequency current to the track rails of the first section to the rear, car carried apparatus comprising an electron discharge device, a control relay normally energized by a circuit including said electron discharge device 10

and means for diminishing the flow of current through said electron discharge device and thereby de-energizing said relay in response to said predetermined high frequency current flowing in the track rails.
